CLAIM

The ornamental design for a rotating storage rack assembly, as shown and described.

DESCRIPTION

FIG. 1 is a front perspective view of a rotating storage rack assembly according to an embodiment of my new design;
FIG. 2 is a front elevational view thereof;
FIG. 3 is a rear elevational view thereof;
FIG. 4 is a left side elevation view thereof; and
FIG. 5 is a right side elevational view thereof.
FIG. 6 is a top plan view thereof; and,
FIG. 7 is a bottom plan view thereof.
The broken lines shown herein are for illustrative purposes only and form no part of the claimed design.
